Inventor,

Jacob Wasserberger,

by James P. Duhamel,
Attorney.

UNITED STATES PATENT OFFICE.

JACOB WASSERBERGER, OF NEW YORK, N. Y., ASSIGNOR TO S. H. POMEROY COMPANY, INC., OF NEW YORK, N. Y., A CORPORATION OF NEW YORK.

METAL WINDOW.

Application filed February 23, 1922. Serial No. 538,676.

To all whom it may concern:

Be it known that I, JACOB WASSERBERGER, a resident of New York city, Bronx county, New York, and a citizen of the United States, have invented certain new and useful Improvements in Metal Windows, of which the following is a specification.

This invention pertains to the structural relations of the sash and jamb of a metal window and has for its object to provide for effective prevention of the passage of air between the jamb and the sash without increasing materially the cost of construction or the difficulty of assembling the sash and frame and without interfering with the free movement of the sash. The invention will be more fully explained hereinafter with reference to the accompanying drawing in which it is illustrated and in which—

20 Figure 1 is a view in horizontal section through one side member of a window frame or jamb constructed in accordance with the invention, portions of the two co-operating sashes being also shown.

25 Figure 2 is a view of the same partly in elevation and partly in vertical section.

Figure 3 is an edge view of a portion of one sash, the lintel or frame head being indicated in section.

30 In the embodiment of the invention shown the side frame member or jamb or weight box 5 is shown as composed mainly, as usual, of a single sheet of metal bent into substantially rectangular form, but having, in the

35 present instance, its edge portions 6, 7, bent inward and then in parallelism with the face of the jamb, as clearly shown in Figure 1. The opening between the edge portions of the jamb is closed by a strip which has a central projecting portion 8, standing nearly flush with the faces 23 of the jamb, and lateral flanges 9, such strip being secured to the edge portions 6 as by screws 10. To the central rib or projecting portion 8 is secured, as by screws 14, which may enter bosses 12, a strip 13 which partly overlaps the jamb pockets 15, leaving comparatively narrow slots to receive the flanges of the sashes.

40 Each side member of each sash is formed of two members 17 and 18 which receive the glass 16 between them and are suitably

bowed at 19, are brought together as at 20 to form a flange and are secured together by any suitable means as by screws 21. One of the members, as 17, is extended beyond the other and bent to form a rounded offset 22 to co-operate with the corresponding edge of the flange 9 of the central member so as to form a close joint therewith. It will be noted that the plate or strip 13 leaves between its edges and the opposing angles of the main jamb member, slots or channels in which the sash flanges may move with a free sliding fit.

45 The co-operation of the offset portions 22 of the sash flanges with the flanges 9 and the sliding fit of the flanges in the slots described together effectively prevent the entrance of air and moisture. At the same time the sash and frame can be assembled 70 readily before the central strip 13 is put in place and all of the parts then retained in working relation by securing the filling strip 13 to the closing strip 8, 9.

50 The usual chains, not shown, attached at 75 one end to the weights 11, and passing over the usual pulleys at the top of the frame, pass down within the chain pockets 15 formed by the projecting portion of the jamb and within the plane of the face of 80 the jamb and are secured within the same to the sash flanges.

55 It will be understood that various changes in details of construction can be made to suit different conditions of use and that, except 85 as pointed out in the claims, the invention is not restricted to the particular construction shown and described herein.

I claim as my invention:

60 1. In a window, the combination of a hollow metal jamb having its opposite edge portions bent inwardly and in parallelism with the face, a closing strip having its edge portions secured to the edge portions of the jamb and having a projecting middle portion, whereby a chain pocket is formed with the edge portion of the jamb and within the plane of the face of the jamb, and a sash having a flange entered in the chain pocket and having a rounded offset to co-operate 100 with the wall of the pocket.

65 2. In a window, the combination of a hol-

low metal jamb having its opposite edge portions bent inwardly and in parallelism with the face, a closing strip having its edge portions secured to the edge portions of the jamb, and having a projecting middle portion whereby chain pockets are formed with the edge portions of the weight box, sashes having flanges entered in the chain pockets,

and a filling strip secured to the projecting middle portion of the closing strip to form channels in which the flanges of the sashes move with a sliding fit. 10

In testimony whereof I hereunto affix my signature.

JACOB WASSERBERGER.
